Application April 25, 1949, Serial No. 89,384

7 Claims. (Cl. 101—132.5)

1

Our invention relates to duplicating machines, and more particularly to a liquid process duplicating machine, and is an improvement over the duplicating machine disclosed and claimed in the application of Robert Warren Quirk, Serial No. 63,703, filed December 6, 1948.

It is an important purpose of our invention to provide new and improved driving means for feeding apparatus for feeding sheets one at a time from a feed tray to engage with the master on the drum of a duplicating machine of the character set forth in the above referred to application, said feeding apparatus comprising a primary feeding roller for transferring sheets from a stack one at a time to combined moistening and feeding rollers, from and by which said sheets are then advanced into engagement with the master on the drum. In other words, said feeding apparatus embodies two separate sheet advancing means, one being the primary feeding roller and the other being the combined moistening and feeding rollers.

Our invention provides a driving mechanism for the feeding means that is of a simple and cheap construction, but which is reliable and effective to cause said feeding means first to pick up a sheet from the top of a stack and to feed it into the bite of the pair of feeding and moistening rollers and then to rotate said feeding and moistening rollers so as to feed the sheet into position between an impression roller and the drum on which the master sheet is located, at such a rate that the sheet is traveling at the same speed as the surface speed of the drum when it engages with said drum and impression roller, so as to prevent any buckling of the sheet as it comes into engagement with the master.

It is a further purpose of our invention to provide a driving means of the above mentioned character that is positive in operation, and in which the driving connection between the combined moistening and feeding rollers and the primary feeding roller is entirely gear driven except for one-way clutch means provided for obtaining rotation of the feed rollers in the proper direction.

It is a specific purpose of our invention to provide a driving means for a primary sheet feeding roller and one of the paired feeding and moistening rollers utilized in a duplicating machine of the above mentioned character, said driving means comprising a lever actuated positively in opposite directions by means of a cam, which cam is operated by rotation of the drum carrying the master sheet, said lever being provided with a

2

sector gear portion or curved rack portion that drives a train of gears operating to rotate members forming the driven members of one-way driving means in the form of overrunning clutches connected, respectively, with the primary feed roller that removes the sheet from the stack and with one of the pair of feeding and moistening rollers that feeds the sheet to the impression roller, the overrunning clutch means operating to feed the sheet from the stack when the lever is moving in one direction and the driven roller of the paired feed rollers being actuated when the lever moves in the opposite direction.

Other objects and advantages of our invention will appear as the description of the drawings proceeds. We desire to have it understood, however, that we do not intend to limit ourselves to the particular details shown or described, except as defined in the claims.

20 In the drawings:

Fig. 1 is a vertical sectional view taken longitudinally through the machine forming the subject matter of our invention, partly broken away.

Fig. 2 is a side elevational view of the machine, partly broken away and partly in section, as viewed from the side of the machine provided with the feed roller driving means, the cover plate being removed, said view being taken from the side of the machine appearing at the left in Fig. 3.

Fig. 3 is a vertical transverse section taken on the line 3—3 of Fig. 2, partly broken away.

Fig. 4 is a vertical transverse section taken on the line 4—4 of Fig. 2, partly broken away.

Fig. 5 is a fragmentary plan section taken on the line 5—5 of Fig. 2.

Fig. 6 is a fragmentary plan view of the feed tray and portions of a feed roller and the solvent reservoir.

Fig. 7 is a fragmentary vertical sectional view, taken on the line 7—7 of Fig. 6.

Fig. 8 is a view partly in section and partly in elevation of the one-way clutch mechanism, on an enlarged scale, showing the same mounted on a feed roller shaft, the section being taken substantially on the line 8—8 of Fig. 9 looking in the direction of the arrows, and

Fig. 9 is a transverse sectional view through the one-way clutch mechanism and roller shaft, taken substantially on the line 9—9 of Fig. 3.

As will be pointed out hereinafter, the duplicating machine includes a drum 15, and a pressure roller 271 which cooperates therewith. Disposed in front of the drum and pressure roller, which is to the left, as shown in Fig. 1, and in substantial alignment with the bite thereof, is a

pair of combined feeding and moistening rollers 19 and 251, respectively. Disposed in front of the latter rollers, is a feed tray 140 which is adapted to support a stack of sheets 141, as shown in Figs. 6 and 7. A primary feeding roller 100 is adapted to rest on the feed tray 140 or on the stack of sheets supported thereby, and is disposed in substantial alignment with the bite of the feeding and moistening rollers 19 and 251, and with the bite of the drum 15 and pressure roller 277. The alignment of the parts specified is only "substantial" for the reason that the position of the primary feeding roller 100 undergoes considerable variation, depending upon the height of the stack 141 of sheets on which the primary feeding roller rests.

Means, comprising a supply tank 182, a pump 207 (shown in Fig. 2), suitable conduits, a perforated feed tube 179, and wiping element 153, are provided for supplying a film of moisture to the moistening and feeding roller 19, in a manner substantially similar to that pointed out in the aforesaid pending application.

The manner in which the drum 15 and the feeding and moistening roller 19 are mounted and driven will now be described in detail.

Referring in detail to the drawings, our improved duplicating machine is provided with a frame that includes a pair of side plates 10 and 11, which are connected by means of a plurality of transverse frame members 12. A shaft 13 is journaled in suitable bearings 14 mounted in the side plates 10 and 11. The drum 15 is mounted on the shaft 13 to rotate therewith, hub portions 16 being provided from which the spokes 17 extend to the rim portion of the drum, said hub portions being fixed in position on the shaft 13.

The shaft 13 may be driven in any suitable manner, being shown as being rotated by means of the crank 18, which is provided with a suitable handle 19 and which is fixed to a stub shaft 20 in any suitable manner so as to rotate said shaft by means of said crank. A bracket 21 is provided on the side plate 10 and a bearing 22 for the shaft 20 is provided in said bracket, as well as a bearing 23 in an opening in the side plate 10. A gear 24 is fixed on the shaft 20 between the two bearing members 22 and 23, suitable antifriction washers 25 and 26 being provided between the gear 24 and the bearings 22 and 23. A gear 27 meshes with the gear 24 and is fixed on the shaft 13, an anti-friction washer 28 being provided between the gear 27, which rotates with the shaft 13, and the bearing member 14. The drum 15 is thus rotated by means of the crank 18. The direction of rotation of the drum is counter-clockwise as viewed in Fig. 1, and clockwise as viewed in Fig. 13, arrows being provided on Figs. 1 and 13 to indicate the direction of rotation of said drum.

The side plates 10 and 11 have sheet metal cover plates 29 and 30 detachably mounted thereon providing housings for the driving means for the drum and other moving parts, as will be described below. The shaft 13 has a reduced extension 31 extending into the space between the side plate 11 and the cover plate 30. A collar 32 is fixed on said reduced extension 31 by means of a set screw 33, said collar having an enlargement 34 thereon in which said set screw 33 is screw-threadedly mounted. Said enlargement 34 also has a pair of screw-threaded headed fastening elements 35 engaging in threaded openings therein for securing a cam 36 in fixed position on the collar 32, an anti-friction washer 37 being

5 mounted between the collar 32 and the bearing 14.

6 The cam 36 has a cam groove formed therein between the peripheral flange 38 thereon and the inner flange 39 providing an offset wall portion 40 that forms the bottom of the cam groove. The cam groove has a high portion 41 and a low portion 42 connected by means of the relatively sharply curved portions 43 and 44. The grooved cam 36 rotates with the shaft 13 and thus rotates in a clockwise direction as viewed in Fig. 2. A follower in the form of a roller 45, of a diameter that is equal to the width of the cam groove between the flanges 38 and 39, operates in said cam groove, (see Figs. 2 and 5). Said follower 45 will be moved to the right as viewed in Fig. 2 as the cam rotates from the position shown in Fig. 2. The sharply curved portion 44 of the groove is connected with the low portion 42 by means of a rising portion 46 and as the follower 45 travels along this rising portion 46 of the cam groove it will be moved to the right rather rapidly. It will continue to move to the right as it rounds the sharp turn 44 and will reach the limit of its movement to the right when the junction of the sharply curved portion 44 and the high portion 41 at about the point indicated by the numeral 47 is reached. The follower 45 will then remain in its extreme right position for the entire time that the follower 45 is traveling between the flanges 38 and 39 in the high portion 41. It will begin its movement to the left as it rounds the sharply curved portion 43 of said groove and will move rapidly toward the left back to the position shown in Fig. 2 as the follower travels along the descending portion 48 of said cam. It will be noted that the movement of the follower 45 in both directions will be positive and that it will be positively held in its furthest position to the right from the time that it is engaged by the high portion at approximately the point 47 until it leaves the high portion at approximately the point 49.

45 A pivot pin 50, which has a collar 51 thereon, has the shank portion 52 thereof mounted in an opening in the side plate 11, being fixed in position in said side plate between the flange 53 and the collar 51. A bearing member 54 is mounted on the pivot pin 50 to pivotally mount the sleeve 55 fixed in an opening in the lever 56 on the pivot pin 50. Said lever 56 is fixed to the sleeve 55 by clamping said lever 56 between a shoulder provided on the sleeve 55 and the headed over portion 57 on said sleeve.

55 The lever 56 has a radially extending arm 58 and a transversely extending head portion 59. The radially extending arm 58 has a slight lateral enlargement 60 in which the reduced portion 61 of the pivot member 62 for the follower 60 45 is mounted, said reduced portion being headed over at 63 to fix the pivot pin 62 in the lever 56. The lever 56 will accordingly be oscillated to the right when the follower 45 travels to the right as viewed in Fig. 2, due to the rotation of the 65 cam member 36, and to the left, as viewed in Fig. 2, when the follower 45 is moved to the left due to rotation of said cam member. As a result the lever 56 will be oscillated in a counter-clockwise direction, as viewed in Fig. 2, as the 70 follower travels in the groove toward the high portion 41 thereof and will be moved in a clockwise direction about its pivot, as viewed in Fig. 2, as it travels from the high portion of the cam to the low portion thereof.

75 The movements of the lever 56 will thus be from

the position shown in Fig. 2 rather rapidly toward the right of that position through a predetermined arc, then the lever will remain in its furthest position to the right through a little over half of a revolution of the shaft 13 that has the reduced portion 31, then again rather rapidly through a clockwise oscillation back to the position shown in Fig. 2. The parts will only remain momentarily in the position shown in Fig. 2 because the movement of the follower 45 toward the right as viewed in Fig. 2 will commence as soon as the low point of the cam has been reached. The head portion 59 of the pivoted lever 56 has a sector shaped toothed portion 64 providing a curved rack on said lever and also has the cam surface 65 thereon, which gradually rises toward the left as viewed in Fig. 2. The cam portion 65 is utilized for operating the liquid feeding pump in a manner substantially similar to that pointed out in the aforesaid copending application. The toothed portion 64 operates the sheet feeding mechanism through a train of gears comprising a gear 66 meshing with the teeth 64. The gear 66 is provided on a one-way or overrunning clutch device 67, which has a stub shaft 68 that is mounted in a ball bearing 69 that is provided in an opening in the side plate 11. The stub shaft 68 extends into a bore 70 in the end of a feeding and moistening roller shaft 71, being fixed in said bore to rotate with the shaft 71 by suitable means, such as the set screws 72, (see Fig. 5).

The manner in which the feeding and moistening roller 79 is mounted on the shaft 71 so as to rotate therewith is set forth below. The feeding and moistening roller shaft 71 (see Figs. 4 and 5), is provided with a reduced end portion 73, which is mounted in a ball bearing 74 in the side plate 10, and has a pair of collars 75 and 76 fixed thereon, which are also fixed in reduced end portions 77 and 78 of a tubular roller 79 which comprises the moistening and feeding roller 79. The collars 75 and 76 are, preferably, pressed on the shaft and into the reduced end portions 77 and 78 of said tubular roller 79. Said tubular roller is thus fixed on the shaft 71 to rotate therewith. The roller 79 must rotate in a counter-clockwise direction as viewed in Fig. 1 in the operation of the machine, and accordingly said roller must rotate with the gear 66 when it rotates in a clockwise direction as viewed in Fig. 2. Accordingly the one-way clutch mechanism 67 is so arranged as to drive the shaft 71 when the gear 66 mounted thereon rotates in a clockwise direction and to release so as to have the shaft 71 remain stationary when the gear 66 rotates in a counter-clockwise direction. Accordingly the feeding movement of the roller 79 takes place when the toothed sector 64 is swung toward the right, or counter-clockwise about the pivot 50, from the position shown in Fig. 2.

The driving means for the primary feeding roller 100, and the manner in which it is mounted so that it may adjust itself to the height of the stack 141, will now be described in detail. An idler 80 is mounted to rotate about a stub shaft 81 fixed in the side plate 11, a bearing member 82 being provided for said idler 80 on said stub shaft 81, and said bearing 82 also having a plate 83 pivotally mounted thereon, which plate 83 serves as a pivot lever for a feed roller mounting to be described below. The idler 80 has a pair of gear sectors 84 and 85 formed thereon, the toothed portion 84 meshing with the teeth of the gear 66 and the toothed portion 85 meshing with 75

the teeth of an idler 86. The idler 86 is mounted to rotate about a shaft 87 projecting from the plate 83 and having a spacing sleeve 88 provided thereon, a suitable bearing being provided on 5 the shaft 87 for the idler 86. Said idler 86 meshes with a gear 89 that is fixed on a one-way or overrunning clutch member 90 in a manner to be described below, and said one-way clutch member 90 is so arranged that it will drive the stub shaft 91 projecting therefrom when the gear 89 rotates in a clockwise direction as viewed in Fig. 2.

However, the arrangement of gears and idlers 80 and 86 is such that when the gear 66 is rotating in a clockwise direction the gear 89 will be rotating in a counter-clockwise direction, and vice versa. Accordingly the shaft 91 will be driven by its one-way clutch means 90 from the gear 89 when the shaft 68 is not being driven through its one-way clutch mechanism 67.

A bearing sleeve 92 is fixed in an opening in the plate-like member 83 near the extremity thereof opposite that pivoted on the pivot member 81. A flanged bearing member 93 is mounted in the sleeve 92 and a shaft coupling 94 is fixed to the stub shaft 81 by means of set screws 95. Said shaft coupling 94 is pinned to the shaft 96 by means of the cross pin 97. Thus the shaft 96 will rotate with the shaft 91.

The plate 83 constitutes an arm or lever that is pivoted about the axis of the shaft 81. A similar plate-like member is provided on the opposite side of the machine, similarly pivotally mounted. The shaft 96 is rotatably mounted in the other plate-like member in a suitable manner and a rod 98 connects the arms or plate-like members. Said rod 98 may have a sleeve 99 of suitable cushioning material thereon to serve as a handle for moving the arms or levers about their pivotal axes and thus the shaft 96 about said pivotal axes. The shaft 96 is provided with one or more rollers 100, which are made of compressible material and which have a hub portion 101 that is fixed to the shaft 96 so that said roller or rollers rotate with said shaft. The shaft 96 and the rod-like member 98 operate in slots 102 in the side plates 10 and 11 and the shaft 96 and roller 100 have a limited arcuate movement about the axis of the pivot 81 determined by the length of the slots 102.

One of the one-way clutch mechanisms is shown in detail in Figs. 8 and 9. As both of the one-way clutch devices are of the same general construction, the details of construction of only one thereof is shown. The one-way clutch member shown in Figs. 8 and 9 is shown as being the clutch 67 carrying the gear 66. The body portion of the clutch 67 is rotatably mounted on the stub shaft 68 and said shaft 68 has an annular groove 103 therein, in which the retaining ring 104 is mounted, a spring 105 being mounted between the face of the gear portion 66 of the clutch member 67 and the retaining ring 104. The stub shaft 91 is similarly provided with a groove in which a retaining ring 104 is mounted and between which and the face of the gear portion 89 of said clutch 90 a spring 105 is provided.

Referring now to Figs. 8 and 9, the body portion of the clutch member 67 is provided with an annular laterally extending flange 106 providing an annular shoulder 107 surrounding a recess in one face of said body portion. Said recess has a bottom wall 108, from which the annular rib 109 projects and a central hub-like portion 110. The driven member 111 of the clutch is mounted

in fixed position on the shaft 68 by means of a transversely extending slotted pin 112, which extends through a suitable opening in the shaft 68, and is mounted in diametrically opposed recesses 113 in said driven member 111. The driven member is substantially disk-like in character, being mounted on the shaft 68 so as to extend slightly into the recess bounded by the shoulder 107, and has a transverse opening 114 therein, in which a driving pin 115 is mounted in fixed position, said pin 115 projecting into the recess, as will be clear from Fig. 8.

Surrounding the shaft 68 and mounted between the member 111 and the body portion of the clutch 67 at the hub portion 110 thereof is a spring 116, which is substantially of a circular character except for the ends 117 and 118 projecting radially from the circular body portion thereof. Also mounted between the main body portion of the clutch 67 and the driven member 111 and engaging the inner face 119 of the driven member 111 the annular rib 109 and the hub portion 110 are a pair of clutch members 120 and 121. The clutch member 121 has a slot 122 therein that is open at its outer end and slidably receives the pin 115. Said clutch member has a concave inner face 123, against which the curved body portion of the spring 116 seats, and has an outer curved surface 124, which extends from the slot 122 to the curved end 125 of said clutch member 121. The curved outer surface 124 of the member 121 is curved on a long radius of curvature from the slot 122 to a portion of much sharper curvature 126, which engages the annular shoulder 107 provided on the main body portion of the clutch, said more sharply curved portion 126 extending to the end portion 125, which is of a curvature of still smaller radius, and the curved portion 125 seats in a correspondingly curved recess or socket 127 in the other clutch member 120. The clutch member 121 also has a recess 128 comprising a socket portion adapted to receive the curved end portion 129 of the clutch member 120.

The clutch member 120 is of a generally triangular character, having a central projection 130 that has an outer end wall 131 that is curved to the same radius of curvature as the shoulder 107 and is in engagement with said shoulder. Said clutch member 120 also has an arm 132 at one end thereof that has an outer curved surface 133 that is of the same radius of curvature as the shoulder 107. The inner face of the member 120 has a curved wall 134 engaged by the curved body portion of the spring 116. The ends 117 and 118 of the spring engage with end wall portions 135 and 136 of the clutch members 121 and 120 and normally hold the inclined end faces 137 and 138 of the clutch members 120 and 121 spaced from each other, as shown in Fig. 9. Also the curved toe portion 139 on the clutch member 120 is normally spaced from the socket 128 and the end wall portion 139 of the clutch member 121.

The clutch members 67 and 90 both operate to drive the shafts that these connect with the gears 66 and 89 when said gears 66 and 89 are rotating in a clockwise direction, as viewed in Fig. 2. In other words, the clutch member 67 operates to rotate the shaft 68 in a counter-clockwise direction when the body portion of the clutch member 67 is rotating in such a counter-clockwise direction, as viewed in Fig. 9. The spring member 116 normally operates to hold the portions 131 and 133 of the clutch member 120 in engagement with the shoulder 107, and the curved por-

tion 126 of the clutch member 121 in engagement with said shoulder. Upon rotation of the driving member of the clutch in a counter-clockwise direction, as viewed in Fig. 9, the tendency is for the engaging portion of the member 121 to move in such counter-clockwise direction, which will cause the end of the member 121 that has the slot 122 therein to move outwardly relative to the pin 115. This causes the curved outer face of the clutch member 121 to be tightly clamped or pressed against the shoulder 107 as the rocker or toe portion 125 of said clutch member 121 tends to rotate in a clockwise direction in the socket 127, thus locking the member 121 to the body portion of the clutch 67 and driving the pin 115 and thus the shaft 68 in a counter-clockwise direction, as viewed in Fig. 9.

However, when the gear 66 is rotated in the opposite direction the main body portion of the clutch member 67 will rotate in a clockwise direction, as viewed in Fig. 9. When such rotation takes place, the tendency is for the end of the clutch member having the slot 122 therein to move inwardly relative to the pin 115 as the clutch member 121 is moved slightly in a clockwise direction, as viewed in Fig. 9. This will cause the spring 116 to be tensioned and the ends 117 and 118 thereof to be moved toward each other. Only a very slight amount of such movement is necessary, for any movement of the ends 117 and 118 toward each other will cause rotation of the end 125 of the clutch member 121 in the socket 127 in a counter-clockwise direction, disengaging the curved contact portion 126 of the clutch member 121 from the annular shoulder 107 and causing the curved end portion 129 of the clutch member 120 to move toward the socket 128. Thus the clutch member 121 is released by a very slight movement of the end wall 138 thereof toward the end wall 137 of the member 120 and as a result the clutch will slip as long as rotation of the annular flange 106 is in a clockwise direction, as viewed in Fig. 9. However, the spring 116 is yieldingly urging the members 120 and 121 apart and thus the contacting portions 131, 133 and 126 thereof toward the shoulder 107. Accordingly, as soon as rotation in a counter-clockwise direction of the flange 106, as viewed in Fig. 9, occurs, the clutch will again grip, as described above, to rotate the shaft 68 with the gear 66.

The roller 100 serves as means for removing the sheets of paper to be fed into the machine from a stack one at a time, rotating in a counter-clockwise direction, as viewed in Fig. 1, to accomplish this. The sheets to be fed are mounted in a feed tray that has a body portion 140 providing a flat surface upon which the stack of sheets to be fed rests, one of said sheets being shown at 141. The feed tray, as shown in Figs. 6 and 7, also has depending side flanges 142 and end flanges 143, and may be of a reversible character, similar to that described in the application of Robert Warren Quirk, above referred to.

In operation, assuming that the master sheet 65 has been suitably clamped on the drum 15, and that a stack of copy sheets 141, are disposed on the feed tray 140, the duplicating operation is effected by rotation of the crank 18. When such rotation takes place, the cam 35 is rotated in a clockwise direction, as viewed in Fig. 2, and the arm 56 is swung to the right, as viewed in Fig. 2. This causes a clockwise rotation of the gear 66 and a rotation of the combination feed and sheet moistening roller 19. At the same time the cam 70 65 operates the pump 207 to feed solvent liquid

through suitable conduits to be discharged from the feed tube 170 onto the roller 79 and the wiper pad 156 at the trough-like groove provided between said roller and wiper pad. After the cam has rotated sufficiently that the follower engages the portion 47 thereof, the movement to the right of the arm 56 halts and is not resumed until the portion 49 of the cam reaches the roller 45. When this takes place, then the arm 56 rotates again toward the left to the position shown in Fig. 2 and as this rotation takes place, the gear 66 is rotated counterclockwise. This causes a clockwise rotation of the gear 89 and rotation of the primary feeding roller 100 to feed a sheet from the stack into the bite of the moistening and feeding rollers 79 and 251, the sheet being guided into proper position relative to said rollers by the guide portions 153 and 189 of the guide members that have the inclined portions 152 and 162. The rotation of the moistening and feeding rollers 251 and 79 does not take place, however, until the primary feeding roller 100 has finished its rotation and the cam moves beyond the position shown in Fig. 2 in its clockwise rotation. Then another movement in a clockwise direction of the gear 66 takes place in the manner above described; the sheet is moistened on the surface thereof engaging the roller 79 and is fed into engagement with the drum 15 and into position between the impression roller 277 and the master on the drum 15. The rate of rotation of the roller 79 is such that the sheet will have the same lineal speed as the surface of the drum 15. The oscillation of the arm 56 under the influence of the cam 36 will be repeated in the above referred to manner as the drum is rotated to feed successive sheets into engagement with the master on the drum.

What we claim is:

1. In a duplicating machine, a drum, means for rotating said drum, a sheet feeding and moistening roller, a feed tray adapted to support a stack of sheets, a roller for removing a sheet from said stack and feeding said sheet to said feeding and moistening roller, and means for intermittently and successively rotating said rollers upon rotation of said drum, comprising a member moved back and forth between two alternative positions by rotation of said drum, a pair of rotatable members, a gear drive between said first member and said rotatable members simultaneously rotating said rotatable members in opposite directions, said gear drive including a gear train connecting said rotatable members and means connecting said rotatable members with said rollers to rotate said rollers with said rotatable members only in a sheet feeding direction.

2. In a duplicating machine, a drum, means for rotating said drum, a sheet feeding and moistening roller, a feed tray adapted to support a stack of sheets, a roller mounted for movement toward and away from said feed tray for removing a sheet from said stack and feeding said sheet to said feeding and moistening roller, and means for intermittently and successively rotating said rollers upon rotation of said drum, comprising a member moved back and forth between two alternative positions by rotation of said drum, a pair of rotatable members, a gear drive between said first member and said rotatable members simultaneously rotating said rotatable members in opposite directions and each alternately in opposite directions, and means connecting said rotatable members with said rollers to rotate said

70
75

rollers with said rotatable members only in a sheet feeding direction.

3. In a duplicating machine, a drum, means for rotating said drum, a sheet feeding and moistening roller, a feed tray adapted to support a stack of sheets, a roller mounted for movement toward and away from said feed tray for removing a sheet from said stack and feeding said sheet to said feeding and moistening roller, and means for intermittently and successively rotating said rollers upon rotation of said drum, comprising a pivoted member positively moved back and forth between two alternative positions by rotation of said drum, a pair of rotatable members, a gear drive between said pivoted member and said rotatable members simultaneously rotating said rotatable members in opposite directions, said gear drive including a gear train connecting said rotatable members and movable with said roller toward and away from the surface of said feed tray and means connecting said rotatable members with said rollers to rotate said rollers with said rotatable members only in a sheet feeding direction.

25 4. In a duplicating machine, a drum, means for rotating said drum, a sheet feeding and moistening roller, a feed tray adapted to support a stack of sheets, a roller for removing a sheet from said stack and feeding said sheet to said feeding and moistening roller, and means for intermittently and successively rotating said rollers upon rotation of said drum, comprising a member oscillated between two alternative positions by rotation of said drum, a pair of rotatable gears,

30 35 a toothed portion on said member meshing with one of said gears, a positive driving connection between said gears to simultaneously rotate the same in opposite directions, and means connecting said gears with said rollers to rotate said

40 rollers with said gears only in a sheet feeding direction.

5. In a duplicating machine, a drum, means for rotating said drum, a sheet feeding and moistening roller, a feed tray adapted to support a stack of sheets, a roller for removing a sheet from said stack and feeding said sheet to said feeding and moistening roller, and means for intermittently and successively rotating said rollers upon rotation of said drum, comprising a member mounted for swinging movement, a cam rotating with said drum, a follower engaging said cam to positively swing said member back and forth between two alternative positions, a pair of rotatable gears, a toothed portion on

50 55 said member meshing with one of said gears, a positive driving connection between said gears to simultaneously rotate the same in opposite directions, and means connecting said gears with said rollers to rotate said rollers with said gears only in a sheet feeding direction.

6. In a duplicating machine, a drum, means for rotating said drum, a sheet feeding and moistening roller, a feed tray adapted to support a stack of sheets, a roller for removing a sheet from said stack and feeding said sheet to said feeding and moistening roller, a pair of arms mounting said roller for swinging movement toward and away from said feed tray, and means for intermittently and successively rotating said rollers upon rotation of said drum, comprising a member oscillated between two alternative positions by rotation of said drum, a pair of rotatable gears, a toothed portion on said member meshing with one of said gears, the other of said gears being mounted on one of said arms,

11

a train of gears mounted on said arm between said pair of gears to rotate the same in opposite directions, and means connecting said gears with said rollers to rotate said rollers with said gears only in a sheet feeding direction.

7. In a duplicating machine having a drum and pressure roll disposed in engagement with each other and forming a bite, and a feed tray disposed in substantial alignment with said bite and adapted to support stacked sheets, the combination of two spaced sheet feeding rollers disposed in substantial alignment with said bite, one of said rollers comprising a primary feeding roller and being disposed above said feed tray, and the other of said rollers being a combined feeding and moistening roller and being disposed between said primary feeding roller and said bite, and means for intermittently and successively rotating said rollers, upon rotation of said drum, only in a sheet feeding direction, so that a sheet 20 may be advanced by said primary feeding roller from said stack into engagement with said combined moistening and feeding roller while the latter is stationary, and so that said sheet will be subsequently advanced by said combined feeding and moistening roller in timed relationship with the rotation of said drum into said bite, said roller rotating means comprising an oscillating member pivotally mounted on a side frame of said machine, means actuated by the rotation of said drum for oscillating said oscillating member, a pair of rotatable members, one for each of said rollers, and each being coaxially mounted with respect to said rollers, a gear sector carried by said oscillating member, and a gear train extending from said rack and including gears af-

fixed to each of said rotatable members, said gear trains including an even number of gear elements connecting said rotatable members so that said rotatable members will be rotated thereby simultaneously in opposite directions, the direction of rotation of said gear train being reversed as said oscillating member oscillates, and overrunning clutch means interposed between said rotatable members and said rollers to cause said rollers to be driven by said rotatable members only in a sheet feeding direction, whereby said primary feeding roller will be positively driven only when said gear train is rotating in one direction and said combined feeding and moistening roller will be positively driven only when said gear train is rotating in the reverse direction.

CARL A. LEVIN.
